CLOTHESLINE MOUNTING MEANS

William K. Henry, Richmond Beach, Wash.

Application August 9, 1946, Serial No. 689,489

4 Claims. (Cl. 211—119.15)

1

This invention relates to clothes line mounting means and an object of this invention is to provide simple and efficient means for mounting a plurality of clothes lines in such a manner that they can be quickly and easily slackened or tightened to facilitate hanging clothes on said lines or removing clothes from said lines and to keep the clothes at a safe distance from the ground while they are on the clothes lines.

Another object is to provide clothes line mounting means comprising a rotatively supported cross arm, clothes lines each having one end portion secured to a fixed support and the other end portion secured to said cross arm and arranged to wind thereon, and means for rotatively moving the cross arm to vary the tension and sag of the clothes lines.

Another object is to provide clothes line mounting means that will save time and labor and that will make it easier for persons, particularly women, to hang the clothes on the lines and remove them from the lines.

Other objects are to provide clothes line mounting means of simple construction that is not expensive to manufacture, that is easy to install, that is efficient in tensioning and slackening the clothes lines and that is easy to operate.

Other objects of the invention will be apparent from the following description taken in connection with the accompanying drawings.

In the drawings

Figure 1 is an elevation with parts broken away of clothes line mounting means constructed in accordance with this invention.

Fig. 2 is a view on a larger scale than Fig. 1 looking in the direction of broken line 2—2 of Fig. 1 and showing a clothes line tensioning lever in a lowered position.

Fig. 3 is a view partly in section and partly in elevation taken substantially on broken line 3—3 of Fig. 2.

Fig. 4 is a detached perspective view of the top end portion of the post shown in Figs. 1, 2 and 3.

Fig. 5 is a side elevation illustrating an installation of my invention on a wooden clothes line post, fragments only of the post being shown.

Fig. 6 is a view partly in section and partly in elevation showing a modification of my invention that is adapted to be applied to a wooden clothes line post having a wooden cross arm thereon.

Fig. 7 is a detached exploded perspective view of the modification shown in Fig. 6.

Like reference numerals designate like parts through the several views.

Figs. 1 to 4 show this invention as applied to metal clothes line poles or posts. Fig. 1 shows two spaced apart tubular metal clothes line posts 10 and 11 having their respective bottom end

2

portions embedded in blocks 12 of concrete that are preferably set about flush with the surface of the ground. Preferably the portion of each post 10 and 11 that is embedded in the concrete block 12 is provided with one or more rigid outwardly protruding lugs 13 which anchor the post more firmly in the block of concrete and prevent rotary movement of the post.

One of the posts, such as the post 11, is provided with a rigid cross arm 14, which may be welded thereto. A plurality of clothes lines 15 are secured to this cross arm 14 at spaced apart intervals and in any suitable manner.

The other post 10 has a tubular sleeve 16, Fig. 4, secured, as by welding, to its upper end and extending crosswise thereof. The sleeve 16 has a longitudinal slot 17 in its uppermost portion extending from one end thereof to a point above the post 10. The sleeve 16 is also provided with a circumferential slot 18 disposed above the post 10 and extending from the top of the post 10 upwardly and about half way around the sleeve 16 and intersecting the longitudinal slot 17. The top end portion of the post 10 preferably has a notch 19 that registers with the slot 18 in the sleeve 16.

The sleeve 16 is adapted to telescopically receive and rotatively support a tubular metal cross arm 20. The cross arm 20 has an outwardly protruding lever arm 21 fixedly secured thereto. The lever arm 21 is of small enough cross sectional dimensions so that it can be moved lengthwise into and out of the slot 17 and can be moved angularly within the slot 18 between a substantially upright position as shown by full lines in Fig. 1 and a downwardly inclined position, as shown by broken lines in Fig. 1. Obviously angular movement of the lever arm 21 will rotatively move the cross arm 20. The clothes lines 15 wind on and are fixedly secured to the cross arm 20 in such a manner that they will be tightened and loosened by rotary movement of said cross arm 20. One way of securing these clothes lines to the cross arm 20 is to pass them through holes 45 22 in the cross arm 20 and then knot or twist the ends of the clothes lines. The cross arm 20 can be rotatively moved to slacken the clothes lines 15, as shown by full lines in Fig. 1, or to tension said clothes lines, as shown by dot and dash lines.

The lever arm 21 on the cross arm 20 is connected by a link 23 with a manually operated lever 24. The hand lever 24 is fulcrumed, by a pivot 25, on a bracket 26 that is rigid with the upright post 10.

The pivot 25 is positioned far enough outwardly from the post 10 so that the line of pull of the link 23 will be between the center of the pivot 25 and the post 10 when the clothes lines 15 are tensioned and the bottom end of the lever

24 rests against the post **10**. Thus the line tensioning means will be automatically locked by reason of the line of pull of the link **23** passing the center of the pivot **25** when the lines **15** are under tension.

When the lever **24** is moved outwardly and upwardly from the position shown in Fig. 2 the lines **15** will be slackened and the lever **24** will be held in an elevated position, as shown by full lines in Fig. 1, by the weight and pull of the lines **15**. Preferably a plurality of holes are provided in the hand lever **24** to provide for some adjustment of the point of connection of the link **23** with said lever.

The lever arm **24** is within easy reach of a person who is standing on the ground and is easily moved between a slack line position and a tight line position. This clothes line mounting means reduces the labor involved in hanging out and taking down clothes. The lines **15** are adjusted so that when they are slackened they are lowered into a position as shown by full lines in Fig. 1 in which position they are easy to reach but are high enough to keep the clothes that are being hung on said lines clear of the ground. After the clothes are all hung the lever **24** is moved downwardly into the position shown in Fig. 3 thereby tensioning the lines and lifting the clothes to a safe height above the ground. When the clothes are to be taken off the lines said lines are again slackened to lower them into a position within easy reach for the purpose of removal.

Fig. 5 shows the tubular sleeve **16** of this invention secured, as by a weld **27**, to an angle bracket **28** that is applicable to the upper end portion of a wooden clothes line post **29**. The cross arm **28** and operating mechanism therefor, as shown in Figs. 1 to 4, can be used along with the parts shown in Fig. 6 except that a mounting bracket **30** having a base **31** which can be secured to the post **29** by screws **32** will preferably be provided.

In clothes lines that are already installed and in use it is frequently found that wooden clothes line posts, such as the post **33** of Fig. 6 are provided with conventional wooden cross arms **34** having holes **35** therein through which the lines **15** are passed. To adapt this invention to previously installed clothes lines of this type without change or removal of the cross arms **34** I preferably provide bracket and roller and lever means of the form shown in Figs. 6 and 7. The bracket means therein shown comprises a cross bar **36** adapted to extend across and rest against the post **33** and having two upright arms **37** provided with surfaces **38** adapted to rest against the cross arm **34**. Notches **39** in the arms **37** are adapted to receive bearing pins **40** on the ends of a roller **41**, which may be of wood. The roller **41** has suitable holes **42** therein to receive the lines **15**. A lever arm **43** is secured to the roller **41**. A chain **43** on the outer end portion of the lever **42** is adapted to be engaged with a hook **44** in the post **33** to secure the lever **42** to the post **33** and hold the lines **15** under tension. Preferably this chain **43** is long enough so that when the lever **42** is in its raised position the chain **43** can be easily grasped to facilitate pulling the lever **42** down. Obviously the chain **43** provides for securing the lever **42** different adjusted positions depending upon the tightness of clothes lines desired. The bar **36** can be secured to the post **33** if desired but the lines **15** which pass through the holes **35** in the cross arm **34** will support the bar **36** and roller **41** in the proper position even if the

bar **36** is not thus secured to the post **33**. Tension of the lines **15** will prevent displacement of the bearing pins **40** from the notches **39**. The lever **42** is not self locking and in this respect differs from the devices shown in Figs. 1 to 4. In other respects the operation of the devices shown in Figs. 6 and 7 is similar to the operation of the structure of Figs. 1 to 4.

Obviously changes in this invention may be made within the scope and spirit of the following claims.

I claim:

1. Clothes line mounting means comprising an upright post; a horizontal cross arm rotatively mounted on said post; clothes lines each having one end portion secured to a fixed support and the other end portion secured to said cross arm and arranged to wind thereon; a lever arm secured to said cross arm; bracket means carried by said post; a hand lever fulcrumed on said bracket by pivot means positioned at a distance from said post; and a link connecting said lever arm with said hand lever whereby said cross arm may be rotatively moved by swinging movement of said hand lever, the line of pull of said link being between the bracket and the post when the non-pivoted end portion of the lever rests against the post to thereby provide a self-locking structure.

30 2. Clothes line mounting means comprising an upright post; a horizontal sleeve carried by the upper end portion of said upright post; a cylindrical cross arm rotatively supported in said sleeve; clothes lines each having one end portion secured to a fixed support and the other end portion secured to said cross arm and arranged to wind thereon; a lever arm secured to said cross arm; a hand lever pivotally mounted on said post; and a link connecting said lever arm with said hand lever whereby said cross arm may be rotatively moved to vary the tension and sag of said clothes line.

3. Clothes line mounting means comprising an upright post; a cylindrical bearing sleeve rigidly secured to the upper end portion of said post crosswise thereof, said sleeve having a longitudinal slot in its upper portion extending inwardly from one end thereof and having a circumferential slot positioned above the post and intersecting the inner end portion of said longitudinal slot; a cylindrical cross arm rotatively supported in said sleeve; a lever arm secured to said cross arm and extending outwardly therefrom, said lever arm being of smaller cross sectional dimensions than said slots whereby it is movable in said slots; clothes lines each having one end portion secured to a fixed support and the other end portion secured to said cross arm and arranged to wind thereon; and means for moving said lever to vary the tension of said clothes lines.

4. Clothes line mounting means comprising an upright post; a horizontal cross arm rotatively mounted on said post; clothes lines each having one end portion secured to a fixed support and the other end portion secured to said cross arm and arranged to wind thereon; a lever arm secured to said cross arm; a hand lever pivotally mounted on said post; and a link connecting said lever arm with said hand lever whereby said cross arm may be rotatively moved to vary the tension and sag of said clothes line.

WILLIAM K. HENRY.
